CLAIM

The ornamental design for a fabric softener dispenser, as shown and described.

DESCRIPTION

FIG. 1 is a top, front, and left side perspective view of a fabric softener dispenser showing my new design, the broken-line disclosure of a roll being for illustrative purposes only and forming no part of the claimed design;

FIG. 2 is a front view thereof;

FIG. 3 is a rear view thereof;

FIG. 4 is a bottom view thereof; and,

FIG. 5 is a top view thereof.

1 Claim, 3 Drawing Sheets
